CLAIM

The ornamental design for a bread basket, as shown and described.

DESCRIPTION

FIG. 1 is a top, front right perspective view of a bread basket showing the new design;

FIG. 2 is a front view of the bread basket of FIG. 1;

FIG. 3 is a rear view of the bread basket of FIG. 1;

FIG. 4 is a right side view of the bread basket of FIG. 1;

FIG. 5 is a left side view of the bread basket of FIG. 1;

FIG. 6 is a top view of the bread basket of FIG. 1; and,

FIG. 7 is a bottom view of the bread basket of FIG. 1.

The broken lines shown in the figures depict portions of the bread basket that form no part of the claimed design.

1 Claim, 4 Drawing Sheets(56)
